UNITED STATES PATENT OFFICE.

ARTHUR K. MILLER, OF PEEKSKILL, NEW YORK
BEST AVAILABLE COPY
LAMP.

1,070,161.

Specification of Letters Patent. Patented Aug. 12, 1913.

Application filed July 22, 1910. Serial No. 573,169.

To all whom it may concern:

Be it known that I, ARTHUR K. MILLER, a citizen of the United States, and resident of Peekskill, in the county of Westchester 5 and State of New York, have invented certain new and useful Improvements in Lamps, of which the following is a specification.

The object of my invention is to provide a 10 lamp adapted for automobiles, boats, and other vehicles, which shall be simple and cheap to construct, shall be strong and efficient in use, and which will do away with the objections to external supports or 15 brackets at the sides of the lamp body that are customarily provided with lamps of this character.

My invention comprises novel details of improvement and combinations of parts that 20 will be more fully hereinafter set forth and then pointed out in the claims.

Reference is to be had to the accompanying drawings forming part hereof, wherein;

Figure 1 is a sectional view of a lamp embodying my invention on the plane of the line 1, 1, in Fig. 2; Fig. 2 is a horizontal section, enlarged, on the plane of the line 2, 2, in Fig. 1; Figs 3 and 3^a are details of universal supporting means for the lamp; 25 Fig. 4 is a detail perspective of the means for retaining the mirror or reflector in place; Fig. 5 is a detail section illustrating means for supporting my invention upon the frame of an automobile. Fig. 6 is a similar 30 view of a modification; Fig. 7 is an edge view, looking in the direction of the arrows on the dotted line 7, 7, in Fig. 6.

In the drawings the numeral 1 indicates the main casing or body of the lamp, which 40 may be of any suitable construction, shown provided with a swinging door 2 in usual manner. At 3 are supporting and strengthening bands secured to body 1, which bands fit against the surface of said body, being 45 shown fitted along and corresponding in shape to the inner surface of body 1 so as to bear snugly against said body, bands 3 being shown secured to the body 1 by rivets 4, 5. Said rivets 5, are shown holding cap 50 1^b in place on the body. The lower ends of bands 3 project downwardly at 3^a through suitable openings in the lamp body and serve as supports therefor. By having the parts 3, 3^a made integral and suitably riveted or 55 bolted to the lamp body the latter is reinforced and braced and the parts will remain

in proper relation, and the necessity of providing brackets or supports on the exterior of the lamp body is obviated, whereby the main exterior of the lamp body may be left free and unobstructed, may be easily cleaned, and the cost of producing the same is reduced.

The mirror or reflector 6 is shown fitted along the rear wall of lamp body 1 and provided with retaining ring 7 having the flange 7^a against which screws 8 bear, which screws mesh in threaded apertures in brackets 9 fastened to bands 3, as by rivets 10. By this means the mirror or reflector 70 can be readily removed and replaced when required by merely operating screws 8, and the reflector will be properly retained in position within the lamp, flange 7^a being held firmly against the back wall 1^a of the 75 lamp body.

The projections 3^a may be supported in any suitable manner, for which purpose I have shown several forms of construction. In Fig. 1 a yoke 11 incloses projections 3^a and is secured to band 3 and body 1 by rivets 4, and said yoke is adapted to be supported by a bracket 12, as by a screw or bolt 13 passing through the same. A suitable burner 14 may be carried by lamp body 1 as indicated, or in other suitable manner, and the lamp body may be provided with suitable air holes 15.

In Figs. 3 and 3^a the yoke 11, instead of being rigidly attached to the lamp body, is 80 movably attached thereto by means of bolts 16 passing through the side members of the yoke and through the projections 3^a, a brace 17 by preference being interposed. Screw or stud 13 may pass through any suitable 85 bracket, such as 12^a, in manner before described for holding yoke 11 in position, and the lamp body may be tilted and set in desired position by operating the bolts 16.

In Fig. 5 the yoke 11 is shown secured to 90 band 3 and the lamp body substantially as in Fig. 1, and the bolt 13^a passes through holding bars 17^a that rest upon the frame 18 of the automobile, and are held by bolt 19. By this means the lamp may be adjusted in 95 the desired position.

Where the lamp is to be adjusted on a curved support, such as upon the curved goose-neck 18^a of an automobile frame, (see Fig. 6), I may extend the projections 100 3^a down to embrace the part 18^a and bend said projections at 3^b to fit snugly against

the frame part 18^a, and connect the projections 3^a by bolts 20, and in order to assist in bracing the projections 3^a at the curved portion of frame part 18^a to give the lamp an upright position, I may apply a block 21 within part 18^a and provide said block with a threaded extension 21^a receiving nut 22, which block may be curved at its corners to enable it to be jammed in the channel of part 18^a to aid in supporting the projections 3^a in the desired position.

Having now described my invention what I claim is:—

1. A lamp comprising a body, reinforcing bands extending along the inner surface of said body on opposite sides and secured to said body, said bands projecting through the lower portion of the body, and supporting means attached to said bands.
2. A lamp comprising a body, reinforcing bands within said body and extending along in substantial alinement with the inner surface thereof on opposite sides of the body, said bands being secured to the body near the upper and lower parts thereof, said bands having projections extending through the lower portion of the body, and supporting means attached to said bands.
3. A lamp comprising a body, reinforcing bands located within the body on opposite sides thereof and secured to said body, said bands having portions projecting through the lower portion of the body, a support for the lamp, and means for movably connecting said support with said projections.
4. A lamp comprising a body, reinforcing bands extending along the surface of the

body on opposite sides thereof, a yoke attached to said bands, and a bracket attached to said yoke.

5. A lamp provided with a reflector, a frame having an inner marginal portion in front of the edge portion of the reflector, and having a flange extending outwardly beyond the reflector and bearing against the rear wall of the lamp, the lamp body having brackets in front of the flange, and screws carried by the brackets and bearing against said flange to push the latter against the rear wall of the lamp body, whereby the frame retains the reflector against the rear wall of the lamp.

6. A lamp comprising a body, re-inforcing bands extending along the inner surface of the body on opposite sides and secured to said body, brackets connected with said bands, a reflector at the rear of the lamp body, a frame receiving said reflector and having a portion bearing against the margin of the latter, said frame having a radial flange bearing against the rear wall of the lamp body, and screws carried by said brackets and bearing against said flange to hold the latter against the lamp body for retaining the reflector between the lamp body and said frame.

Signed at New York city, in the county of New York, and State of New York, this 19th day of July, A. D. 1910.

ARTHUR K. MILLER.
